TO BENJAMIN ELECTRIC MANUFACTURING COMPANY, OF CHICAGO, ILLINOIS, A
CORPORATION OF ILLINOIS.

PLUG FOR INCANDESCENT ELECTRIC LAMPS.

1,125,605.

Specification of Letters Patent.

Patented Jan. 19, 1915.

Application filed May 13, 1912. Serial No. 696,868.

To all whom it may concern:

Be it known that I, WILLIAM C. TREGONING, citizen of the United States, residing at Cleveland, in the county of Cuyahoga and State of Ohio, have invented certain new and useful Improvements in Plugs for Incandescent Electric Lamps, of which the following is a specification.

This invention appertains to plugs for incandescent electric lamps, all substantially as shown and described and particularly pointed out in the claims.

In the accompanying drawings, Figure 1 is a side elevation of the plug showing a section of the strand which presumably has the lamp socket at the other end and with the parts of the plug in unlocked relation. Fig. 2 is a side elevation corresponding to Fig. 1, but with the parts interlocked and the strand untwisted. Fig. 3 is an enlarged central sectional elevation of the plug in disengaged relations, as in Fig. 1. Fig. 4 is a bottom view of Fig. 5, and Fig. 5 is a sectional elevation of the porcelain or like body or head of the plug with certain parts attached thereto as hereinafter described. Fig. 6 is a sectional elevation of a modification of the flexible connecting mechanism between the two non-conducting parts of the plug as hereinafter fully described.

Many different makes of plugs have been on the market from time to time and which may be divided into two types according to their construction, one of said types having the conducting cord or strand fixed therein so that when the plug is turned to screw it into its socket the strand will turn with it and become twisted accordingly, and the other type having the strand so related therein that the plug can be screwed into the socket and the strand will not turn with it and hence not become twisted.

Without discussing the acknowledged objections to both forms or types as heretofore made the present invention enters the art as it were between both, having the strand so connected that it will receive a partial twist when screwing up of the plug occurs but also such that it will untwist automatically as the part grasped by the hand is momentarily released to take a new grip, and this action will continue and wind and unwind the strand as often as the hand is changed until at last when turning of the

plug ceases the strand will resume its straight or natural condition as the locking engagement of the parts is relaxed.

Now, observing the plug first in its structural aspects, we have the non-conducting body or head *b*, upon which the other parts are directly or indirectly mounted, and the said body has a metallic band *2* about its reduced portion which has one or more recesses *3* struck in its side adapted to make rotary interlocking engagement with lugs *4* struck on the inside of the screw shell *5* when said band is pressed upward for this purpose and to rotate the said shell. Obviously the said recesses and lugs could be interchanged as to the parts and be the same in effect. The said body *b* has a milled rim about its side adapted to be conveniently gripped by the hand to turn the plug, and when turning occurs (and assuming that the plug is in an inverted position to that shown in the drawings) the said body is pressed upward into engagement with the said lugs *4* and turned and thereby turning the screw shell in its socket, not shown. When the hand has turned as far as is comfortable the grip is released, the said body *b* drops by gravity, and any twisting of the connecting strand that has occurred instantly rights itself. Then another grip is made with a further turn of the plug and so on until the plug is screwed home into its socket and electrical connection is completed. Of course the instant the up-lift upon the body *b* is released it drops down and is free to rotate regardless of said shell *5* but electrical connection remains through or between the said shell and ring *2* which in any case overlap sufficiently for this purpose. A terminal binding screw *6* is shown as engaged in an ear on the band *2* as seen in Figs. 4 and 5.

It follows from the foregoing that the body or head *b* is supported in a sliding relation within limits upon or about the said shell *5*, and said shell is supported at its other end or edge by several associated parts comprising a stem or standard *7* which is embedded in body *b* and has a threaded hole through its free right angled end adapted to be engaged by a differential screw *8* which is projected centrally through a thimble *9* in a porcelain disk *d* which is supported within the edge of the said screw shell.

The said shell may be engaged with said disk in any suitable way, and the said disk has a central bore occupied by the thimble 9. The screw 8 has a relatively long cylindrical head slidably fitted in the inner portion of said thimble and a body portion of smaller diameter slidably in the neck or contracted inner portion *n* of the thimble. The screw-threaded and relatively reduced extremity 10 of the said screw engages through the threaded hole in the right angled portion of stem 7 and thus an effective support is provided for the outer portion or end of said screw shell 5 while at the same time a conducting electrical connection is formed from the flanged out end 15 of thimble 9 through the said stem or standard 7 or to the binding screw 16 thereon.

The adaptation of the stem or standard 7 to slide within limits through the peculiar construction of screw 8 in thimble 9 provides what may be termed a flexible electrical connection with the said thimble from the body *b*, or rather with the band 3 thereon, and the length of the said body portion of the screw measurably fixes the limit of movement, especially to open position, as in Fig. 1. Therefore, having the plug more or less engaged in its socket, not shown, the head of body *b* can be manipulated, and in a sense it acts like a wrench as it is raised or brought into engaging relations with the screw shell to turn the same, and in this movement the stem or standard 7 and screw 8 participate.

Fig. 6 shows a modification in this particularly that the screw 12 is a stationary part in disk *d* and has a flanged contact head 15' outside said disk and a spool 14 is threaded on said screw outside said disk while the stem or standard 7 has a hole in its right angled portion engaged on said screw and slideable thereon within limits like the screw 8 in spool 9, Fig. 3.

In the foregoing construction the body *b* is freely rotatable in respect to the shell 5 in either direction when disengaged at the points 3 and 4, but the overlapped engagement between said parts is close and in current-conducting condition and the binding screw 6 marks one of the terminal connections as above described. The other terminal carried by the member *b* is at 16 on the stem or standard 7, which presumably is molded into said member in its manufacture. The flanged head 15' and the screw serves to make electrical connections in the plug socket. However, these are details of incidental importance merely as the invention resides essentially in the novelty which operationally separates the body *b* from the screw

shell 5 and in one position leaves said body free to turn in either direction independently of the said shell and in the other position interlocks therewith and becomes an instrument for turning the shell into and out of its 65 socket. Any construction having this peculiarity and function is considered as within the spirit of this invention.

In Fig. 3 if the body *b* be rotated the screw 8 fixed on stem 7 will rotate also in thimble 70 9, and in Fig. 6 the stem 7 will be rotated about the spool 14.

What I claim is:

1. A plug for electric lamps comprising a screw shell of conducting material and a 75 non-conducting part having a ring about the same in sliding relations with said shell, and said shell and ring provided with means constructed to mechanically interlock.

2. A plug for electric lamps having a screw 80 threaded shell, a body of non-conducting material having a normal free rotation in respect to said shell and a metallic band about the same in overlapping relations with said shell, and the said shell and band provided with interlocking portions at their meeting edges.

3. A plug for electric lamps having a screw-threaded metallic shell and a non-conducting body adapted to be engaged and disengaged rotarily therewith, and means supporting the opposite end of said shell comprising a non-conducting part and slidably related conducting means centrally of said several parts.

4. A plug for electric lamps having a screw-threaded metallic shell and a non-conducting body having a contact band about its inner portion and said band and shell provided with means constructed to mechanically interlock, the said body being normally disengaged and free to turn independently of said shell.

5. A plug for electric lamps having a screw-threaded shell and a body slidably and rotatably related thereto having a band about the same in overlapping relations with said shell, a disk of non-conducting material carrying the opposite end of said shell and means supporting said disk comprising a 110 stem fixed in said body, a spool rotatably mounted in said stem and a screw on which said spool is engaged and uniting said stem with said disk.

In testimony whereof I affix my signature 115 in presence of two witnesses.

WILLIAM C. TREGONING.
